BRIDGE TABLE

Application filed February 15, 1929. Serial No. 340,126.

This invention relates to bridge tables.

It is among the objects of the present invention to provide in a bridge table, novel and improved means for retaining the legs thereof in adjusted position.

It is a further object of the present invention to provide a bridge table having foldable legs in which gravity actuated means are provided for retaining the legs in folded or extended position.

Another object of the present invention is to provide in a bridge table having folding legs, means for securing the legs in their folded or unfolded position, said means being actuated by gravity to release or secure said legs.

Other objects of the present invention include the combination and interrelation of parts whereby the whole forms a novel, simple, efficient and durable structure well adapted to meet the demands of economic manufacture.

Other objects and features of the present invention will be apparent from a consideration of the following specification taken in conjunction with the accompanying drawings, in which

Figure 1 is a top plan view partly in section, illustrating one embodiment of our present invention;

Fig. 2 is a sectional view taken on the line 2-2 of Fig. 2;

Fig. 3 is a sectional view taken on the line 3-3 of Fig. 2, showing the leg in locked or folded position and the table in reversed position, and

Fig. 4 is an enlarged detail view similar to Fig. 3 and showing the leg in locked or extended position.

Referring more particularly to the drawings, the invention is disclosed in connection with the usual type of bridge table. It will be understood that the invention may be applied to other types of tables which utilize folding legs and for which improved means for securing the legs is desired.

The bridge table herein illustrated includes a top 10, secured to side members 11, the top and side members being joined by the usual peripheral protecting member 12,

which may be secured to the sides 11 by the provision of screws 13, as indicated in Fig. 1.

In conformity with the usual present-day type of tables of this nature, a leg 14 is pivotally secured in each corner of the table. For pivoting the leg and for providing locking means for the pivotal action thereof, there is associated with the corner of the table, a substantially U-shaped bracket 15, one leg of which, as indicated at 16, is considerably enlarged and suitably bored to provide for the locking means, as will be herein-after described. Within the bracket 15 an internally U-shaped bearing bracket 17 is preferably provided for the provision of a suitable surface for co-operation with the leg 14, the brackets 15 and 17 being secured to the sides 11, by the provision of threaded retaining members 18, as illustrated in Fig. 1.

For pivoting the leg 14, a bolt which includes a head 20 associated with an enlarged cylindrical barrel 21, and including a rounded bearing portion 22 adjacent the barrel 21 and a squared shank 23 terminating in a rounded bearing portion 24, is provided. The squared shank 23 is adapted to extend through a head 25 of the leg 14, which is provided with a squared portion for receiving the squared shank and threaded securing means 25^a are provided between the head and the shank for securely locking the same together. For receiving the bolt 20, the bracket 15 is provided with an enlarged opening through the leg 16, and a smaller opening in the opposite leg to receive the bearing extremity 24. The bearing portion 22 is received within a suitable aperture in one leg of the bearing member 17, while the opposite leg receives a portion of the bearing extremity 24. For providing locking means for the leg, the cylindrical portion 21 of the bolt is provided with a pair of right-angularly disposed recesses 26 and 27. For co-operation with these recesses the leg 16 is provided with diametrically opposite recesses 28 and 29, these recesses being vertically arranged through the leg, the upper recess 28 being adapted to co-operate with the recess 26 of the barrel 21, while the lower recess 29 is adapted to co-operate with the recess 27 of the barrel. Access to the recesses

100

28 and 29 is provided for by extending the recess 29 to the lower face of the leg 16, and closing the recess by a threaded closure plug 30, as shown more clearly in Fig. 4. For 5 locking the bolt and consequently the leg 14 which moves therewith, the upper recess 28 is provided with an elongated pin 31, which is freely slidably therein in response to inertia or gravity, while the recess 29 is provided 10 with a shorter pin 32, also freely slidable therein in response to inertia or gravity. The relative sizes of the pins with respect to the recesses mentioned, are such that the recess may receive the entire length of its respective 15 pin.

The arrangement is such that when the leg is in folded position and the table upside down, the pin 32 is received within the recess 27 of the barrel, as indicated in Fig. 3, while 20 when the leg is in extended position, the pin 31 is received within the recess 26. In both instances, the pins act to lock the leg in the adjusted position, while movement of the table is sufficient to dislodge the pins from 25 their receiving apertures and permit movement of the leg to the opposite adjusted position, wherein gravity will cause the pins to assume the locking position.

From the foregoing it will be readily seen 30 that the present invention provides a novel and improved structure in which a single pivot pin acts jointly as a pivot and a locking means for the leg.

It will be understood that numerous 35 changes and modifications and the full use of equivalents in the structural features of the invention as herein disclosed may be resorted to without departing from the spirit or scope of the invention as outlined in the appended 40 claims.

What is claimed is:

1. In a device of the character set forth, a supporting leg and bracket therefor, means for locking said leg in adjusted position with 45 respect to said bracket, said means including gravitational responsive elements, one of said elements being wholly receivable within said bracket, and a pivoted bolt extending between said leg and said bracket, said elements being 50 arranged to co-operate with said bolt for locking the same.

2. In a device of the character set forth, a supporting leg and bracket therefor, means for locking said leg in adjusted position with 55 respect to said bracket, said means including gravitational responsive elements, said elements being wholly receivable within said bracket, and a pivot bolt extending between said leg and said bracket, said elements being 60 arranged to successively co-operate with said bolt for locking the same, while the remaining element is wholly disposed within said bracket.

3. In a device of the character set forth, a 55 supporting leg and bracket therefor, means

for locking said leg in adjusted position with respect to said bracket, said means including gravitational responsive elements, said elements being wholly receivable within said bracket, and a pivot bolt extending between said leg and said bracket, said elements being arranged to successively co-operate with said bolt for locking the same, while the remaining element is wholly disposed within said bracket, said elements being arranged to lock said bolt by extending between said bolt and said bracket. 70 75

4. In a device of the character described, a table including a top and associated legs, pivoting bolts associated with said legs and movable therewith, said bolts being engageable with the top to provide pivotal union between said legs and top, and gravitational means for locking said bolts against movement. 80

5. In a device of the character described, a table including a top and associated legs, pivoting bolts associated with said legs and movable therewith, said bolts being engageable with the top to provide pivotal union between said legs and top, and gravitational means for locking said bolts against movement, said table including brackets and adapted to receive the extremities of said bolts and to house said gravitational means. 85 90

6. In a device of the character described, a table including a top and associated legs, pivoting bolts associated with said legs and movable therewith, said bolts being engageable with the top to provide pivotal union between said legs and top, and gravitational means for locking said bolts against movement, said table including brackets and adapted to receive the extremities of said bolts and to house said gravitational means, each of said bolts including a head receivable within a bracket, said head having angularly arranged apertures adapted to receive said gravitational means for locking said bolt against movement with respect to said bracket. 100 105 110

7. In a device of the character described, a table including a top and associated legs, pivoting bolts associated with said legs and movable therewith, said bolts being engageable with the top to provide pivotal union between said legs and top, and gravitational means for locking said bolts against movement, said table including brackets and adapted to receive the extremities of said bolts and to house said gravitational means, each of said bolts including a head receivable within a bracket, said head having angularly arranged apertures adapted to receive said gravitational means for locking said bolt against movement with respect to said bracket, said gravitational means including a pair of rectilinearly arranged pins alternately receivable by gravity within the apertures of said head. 115 120 125

8. In a device of the character described, 130

a table including a top and associated legs, pivoting bolts associated with said legs and movable therewith, said bolts being engageable with the top to provide pivotal union between said legs and top, and gravitational means for locking said bolts against movement, said table including brackets and adapted to receive the extremities of said bolts and to house said gravitational means,

10 each of said bolts including a head receivable within a bracket, said head having angularly arranged apertures adapted to receive said gravitational means for locking said bolt against movement with respect to said bracket, said gravitational means including a pair of rectilinearly arranged pins selectively movable by gravity partially from the bracket and into the apertures of said head.

15 9. In a device of the character described, a table including a top and associated legs, pivoting bolts associated with said legs and movable therewith, said bolts being engageable with the top to provide pivotal union between said legs and top, and gravitational

20 means for locking said bolts against movement, said table including brackets and adapted to receive the extremities of said bolts and to house said gravitational means, each of said bolts including a head receivable

25 within a bracket, said head having angularly arranged apertures adapted to receive said gravitational means for locking said bolt against movement with respect to said bracket, said gravitational means including a pair

30 of rectilinearly arranged pins selectively movable by gravity partially from the bracket and into the apertures of said head, one of said pins being adapted to be received within one aperture of said head, while the remaining pin is disposed wholly within said bracket.
